RECORD STRIP CONTROLLED INDIVIDUAL-TYPE CASTING AND COMPOSING MACHINES

Maurice Richard Dewhurst, Coulsdon, England, assignor to The Monotype Corporation Limited, London, England, a British corporation

Application February 20, 1953, Serial No. 338,120

Claims priority, application Great Britain February 13, 1953

5 Claims. (Cl. 199—77)

This invention relates to single-type casting and composing machines and to photo-typographical composing machines and refers particularly to machines wherein positioning mechanisms for a matrix-case or for a master character-plate, as the case may be, are controlled by a record-strip.

In such type casting and composing machines the matrices for any particular layout or font are arranged in a rectangular case, which is movable in two directions in the same plane to position the required matrix accurately over a mould and in the photo-composing machines, the characters are similarly arranged on a master-plate adjustable in the same manner to position a character relatively to a lens for projection on to a light-sensitive surface. In both kinds of machines individual members of two series of gauges are selectively operated under control of the record-strip to govern the positioning mechanisms which control the movements of the matrix-case or master-plate, as the case may be.

The existing gauging and positioning mechanisms for the matrix-case or for the master-plate comprise two pairs of primary positioning jaw-carrying levers co-operating with two stepped series of separately operated primary gauge pins, each of which determines only one positioning point for a matrix-case or for a master-character plate. Each pair of these primary positioning levers adjusts a secondary gauge or stop, and, co-operating with each of these secondary gauges are two pairs of secondary positioning jaw-carrying levers one pair of which moves the matrix-case or master-plate in one direction to the position indicated by one of the secondary gauges and the other pair moves a carrying frame for the matrix-case or the master-plate in another direction to a position indicated by the other secondary gauge.

The present invention is particularly concerned with the primary positioning mechanisms and the primary gauges.

It is the chief object of the present invention to provide primary positioning mechanisms which can determine or dictate two positions of adjustment for a matrix-case or for a master-plate from any one or from a selected number of the primary gauge pins.

According to the present invention there is mounted on the normal jaw of one of the primary positioning levers a second or supplementary jaw which is loosely mounted on the normal jaw and placed in advance thereof and the mechanism controlled from the record-strip acts to render one or other of these jaws operative on any one, or on a pre-selected number, of the gauge pins of the series.

The invention will be described and illustrated as embodied in a die-case positioning mechanism of an existing single-type casting and composing machine, such as described in the specification of British Letters Patent No. 8,633/99.

Referring to the accompanying drawings:

Figure 1 is a plan of the said existing gauging and positioning mechanism showing the mechanism or devices according to the present invention embodied therein.

2

Figure 2 is an enlarged view of part of the mechanism shown in Figure 1.

Figure 3 is a sectional elevation taken on the line 3—3 of Figure 2 and looking in the direction of the arrows 5 shown in Figure 2.

Figure 4 is an end sectional elevation taken on the line 4—4 of Figure 3 showing the devices of the present invention in one position of adjustment.

Figure 5 is a view similar to Figure 3 with the devices 10 of the present invention in one position of adjustment.

Figure 6 is a sectional elevation taken on the line 6—6 of Figure 5 and looking in the direction of the arrows in Figure 5.

Figure 7 is an end elevation viewed from the right 15 hand end of Figure 1 and

Figure 8 is a front elevation of Figure 1.

In the existing machines there are, as already stated, two series of gauging and positioning mechanisms for the matrix-case or for the master plate and, as these two 20 mechanisms are similar, a description of one will serve for both.

Each gauging and positioning mechanism of the existing single-type casting and composing machine comprises: a stepped primary gauge in the form of fifteen 25 gauge pins A each operated by air from perforations in the record-strip, and a primary positioning mechanism comprising a pair of oppositely movable levers A¹, A², co-operating therewith. The lever A¹ is furnished at its outer end with a jaw A³ provided on its forward face with recesses A⁴ (see Figs. 2, 3 and 6) and the lever A² has pivoted to its forward end a jaw A⁵, which after the jaw A³ has contacted with a gauge of the series moves into contact therewith. The levers A¹, A² are coupled together at their rear ends by a link A⁶. Intermediate its 30 ends the lever A¹ is connected by a link A⁷ to a pivot pin A⁸ mounted on an arm A⁹ which is rocked on a stationary pivot A¹⁰. The lever A² is coupled to a stationary pivot A¹¹ by a link A¹². When the rocking lever A⁹ is moved to the right as shown in Figure 1, the lever A¹ is moved 35 to the right until the jaw A³ contacts with whichever of the pins A is raised. The lever A² is then moved until the jaw A⁵ thereon contacts with the opposed jaw A³. In closing on a projected pin of the primary group A, the jaws A³ and A⁵ carry with them the secondary gauge 40 which is formed by a head or stop A¹³ on a sliding bar A¹⁴ and position this stop in line with the projected pin of the series A. On encountering the said pin, the lever A¹ is arrested and the continued movement of the rocking lever A⁵ causes the lever A² to advance towards the 45 left until the jaw A⁵ carried thereon meets the jaw A³. During this closing movement of the levers A¹, A², the jaws A³ and A⁵ have moved the secondary gauge A¹³ into alignment with the raised pin of the series of primary gauges A. The sliding bar A¹⁴ is then temporarily 50 locked by a toothed rod A¹⁵ which engages teeth on the bar. The secondary positioning mechanism which co-operates with the secondary gauge A¹³, comprises a pair of oppositely movable levers A¹⁶, A¹⁷, which carry at their outer ends respectively jaws A¹⁸, A¹⁹. These levers A¹⁶, A¹⁷, are coupled together at their rear ends by a link A²⁰ and the lever A¹⁷ is connected to the pivot pin A⁸ on the rocking lever A⁹ by a link A²¹ whilst the lever A¹⁶ is connected to a stationary pivot A²² by a link A²³ 55 (see Fig. 1). During the closing movement of the jaws A³, A⁵, the secondary positioning levers A¹⁶, A¹⁷, have been opened by the movement of the rocking levers A⁹. On the return movement of the rocking lever, i. e. towards the left hand, the levers A¹, A², are separated leaving the secondary gauges A¹³ stationary and the levers A¹⁶, A¹⁷ are brought together until the jaws A¹⁸, A¹⁹ thereon encounter the secondary gauge A¹³. In clos-

70

ing these jaws A¹⁸, A¹⁹, encounter a stop B connected to the matrix-case B¹.

The matrices b (see Fig. 1) are arranged in columns and rows in the case B¹ which is movable bodily in one direction in a carrying frame B² which in turn is movable in a direction at right angles to the movement of the die-case. As shown in Fig. 1 the stop B is formed on the head of a draw-bar B³ attached to a slide B⁴ in a slot in which a nose B⁵ on the end of the die-case B¹ is free to slide in company with the frame B² in which it is mounted.

In the commercial machine, to which the present invention is applicable, there are fifteen pins in the series of the primary gauge A and correspondingly there are fifteen columns of matrices b in the die-case B¹. Thus one pin is useful only for positioning one row of matrices. In this machine also the gauging and positioning devices described above are, as already stated, duplicated for positioning the frame B², so that by the combined movements of these two groups of positioning and gauging devices a matrix, situated on the point of intersection of these two lines of movement will be positioned over the type-casting mould.

The positioning mechanism for the carrying frame B² of the matrix-case (not shown) is controlled from a rocking lever A²⁴, which is mounted on the pivot A¹⁰. This mechanism is a duplicate of that above-described for the matrix-case.

According to the present invention each, or a selected number, of the gauging pins A may be used individually to determine, as already stated, two different positions of adjustment of the matrix-case. In the example illustrated the die-case is furnished with twenty-one rows of matrices and by the present invention these twenty-one rows can be positioned selectively from the fifteen pins or a lesser number than fifteen.

In accordance with this invention, a supplementary jaw C is hinged on the jaw A³ so as to project in front thereof (see Figs. 1, 2, 3 and 6). This jaw C is furnished on its forward face with three pin-engaging recesses C¹ (see Figs. 2, 3, 4, 5 and 9) similarly to the jaw A³. The hinge between the jaws A³ and C is conveniently formed by a rib C² on the jaw C³ arranged to project into a channel in the underside of a hood a on the jaw A³. The rear end of the jaw rests on the top of the jaw A³. Thus the jaw C is moved backwards and forwards in company with the jaw A³, and in one position of adjustment it is raised above the level of the gauge pins in their operative position (see Fig. 5) and any raised pin is then engaged by the jaw A³. When the supplementary jaw C is lowered on its hinge in front of the jaw A³ (see Fig. 3) it can engage whichever pin of the series A is raised and the jaw A³ is thereby rendered inoperative.

The supplementary jaw C is moved into and out of operative position under control of perforations or signals in the controlling record-strip in which case special signals accompany any character or like designating signals which control the gauging pins of the series A.

In order to render the movements of the jaw C responsive to the record-strip there is furnished on the said jaw a side lug C³ (see Figs. 4 and 6) arranged to move along a channel in a supporting bar D which is mounted on a shaft D¹ at one side of the gauges A (see Figs. 1 and 2).

Connected to a projection D⁶ on the bar D is a rod of a piston D² situated in a cylinder D³ to which air is admitted at d from a conduit controlled by the record-strip. When no air is admitted to the cylinder D³ the bar D remains in the position shown in Fig. 4 and the jaw C is in position to contact with the gauge pins A. A perforation in the record-strip for admitting air to the cylinder D³ will accompany the character designating perforations in the record-strip, which do not require the jaw C to be in operative position. When

air is admitted to the cylinder D³ the piston D² is raised and the jaw C is also raised clear of the pins A (see Fig. 6) by the raising of the bar B. When air pressure is removed from the piston D² the bar D and jaw C are returned by a spring D⁴.

In the arrangement of the relative positions of the jaws A³ and C, above described and shown in the annexed drawings, the first ten pins, counting from left to right, are used with the supplementary jaw C in operation, to bring the first ten columns of matrices in the matrix case in line with the casting mould and the first eleven are used with the jaw A³ in operation, to bring the next eleven columns into alignment with the mould, thus providing twenty-one die-case positions from the fifteen gauge pins.

By a relative setting of the jaws A³ and C, the entire fifteen pins can be used with the jaw C for the first fifteen columns of matrices and the first or last six pins of the series can be used with the jaw A³ for the extra six positions to provide twenty-one positions in all.

The arrangement, in all cases, will be that when the jaw C is in position to contact the last pin of the series A allotted to it, the jaw A³ will be one stage away from the first pin of the series A allotted to it.

The provision of the mechanism of the present invention does not interfere with the use on the machine of a die-case restricted to fifteen rows of matrices. When this use is desired, mechanism is provided for locking the jaw C in lower or operative position and the jaw A³ will not be used. This mechanism comprises a wedge piece E mounted on a slidable bar E¹ (see Figs. 2, 4 and 8). When the bar E¹ is moved to the right from the position shown in Fig. 8 the wedge E passes under a lug D⁵ on the bar D (see Figs. 4 and 6) and prevents the said bar D from being forced up by the controlling piston D².

Likewise a pin F (see Figs. 1 and 2) held in raised position by a spring (see Fig. 8) acts as a stop for a rod B⁶ attached to the slide B⁴ which is coupled to the die-case. This stop prevents the over-throw or over-travel of the smaller sized die-case.

The wedge-carrying bar E¹ and the stop pin F are controlled by hand. The bar E¹ is coupled to an arm G¹ on a shaft G (see Figs. 1, 2, 3, 4, 7, 8) on which are also mounted arms G², G³, supporting a frame G⁴ which extends over the positioning mechanisms. When the frame is moved by hand from the positions shown in full lines in Fig. 8 to that indicated by broken lines on the same figure, the pin F is withdrawn against the action of its spring by an inclined face on a sliding bar F¹ which acts against the pin F² on the pin F. This sliding bar F¹ is connected to an arm F³ mounted on the shaft F. At the same time the inclined piece E is moved under the lug D⁵ on the bar D.

The nose of a die-case having twenty-one rows is arranged to pass under the forward end of the frame G⁴ but the nose of a die-case containing only fifteen rows will be so arranged as to contact with the said frame. Thus, should the machine attendant neglect to set the frame to lock the jaw C in operative position when a smaller matrix-case or master-plate is in use, then the die-case or master-plate in advancing, will shift the frame G⁴ and effect the locking and prevent accident or damage to parts of the machine.

As previously stated, the mechanism of the present invention and the existing gauging and positioning mechanism above described can also be applied to a photo-typographical composing machine, wherein is employed a master character-plate in place of a matrix-case, for example, with the photo-typographical composing machine described and illustrated in the specification of U. S. A. Letters Patent No. 2,388,961.

By means of this invention the primary positioning jaws can determine or dictate two different positions of adjustment for the matrix-carrier or the master-plate from

any single pin of the primary gauges, thus providing for the employment of a considerable increase in the number of matrixes or characters that can be positioned from a given number of primary gauge pins.

What I claim is:

1. In a positioning mechanism for a matrix case of a record strip controlled single type casting and composing machine, or for a master plate of a photo-typographical composing machine, the combination of a pair of mechanically operated and oppositely movable levers, a positioning jaw on each lever arranged to contact individual members of a stepped series of positioning gauge pins which are separately and selectively projected into the path of movement of the jaw under the control of a record strip, to control the position of the matrix case or master plate, a supplementary jaw loosely mounted on the jaw of one of the aforesaid levers and placed in advance thereof, and mechanism controlled from the record strip to move the supplementary jaw into and out of the path of the stepped gauge pins.

2. In a positioning mechanism for a matrix-case of a record strip controlled single-type casting and composing machine or a character-bearing plate of a photo-composing machine, the combination of a pair of mechanically operated and oppositely movable positioning levers each furnished with a jaw co-operating with any member of a stepped series of movable positioning gauge pins, each member of which can be separately projected selectively under control of the record strip into the path of the said jaws, a second or supplementary jaw loosely mounted on one of the said jaws and in advance thereof and mechanism operated by signals in the record strip for moving the supplementary jaw into and out of position to engage or override a projected pin of the series.

3. In a positioning mechanism for a matrix-case of a single-type casting and composing machine or a character-bearing master plate of a photo-composing machine the combination of a pair of mechanically operated oppositely movable die case or master plate positioning levers, a jaw on each lever for co-operating with any one of a stepped series of gauge pins each of which can be projected selectively into the path of the said jaws by signals in the record strip, a supplementary jaw loosely mounted on one of the said jaws and in advance thereof, a sup-

porting bar for the supplementary jaw arranged parallel to the path of motion thereof and mechanism controlled from the record strip for moving the supporting bar and place the supplementary jaw in or out of position either

5 to engage or to override any projected pin of the series.

4. In a positioning mechanism for the matrix case of a record strip controlled single-type casting and composing machine, or for the master plate of a photo-typographical composing machine, the combination of a pair 10 of primary positioning levers, a jaw on each lever, a stepped series of primary positioning gauge pins separately projected under the control of the record strip to contact one of the said jaws, a supplementary jaw hinged to one of said jaws and projecting in advance thereof, a pivoted bar engaging the supplementary jaw, a piston energized under the control of a signal in the record strip to rock the pivoted bar and move the supplementary jaw into and out of a position where it can engage or override a projected gauge pin of the series.

20 5. In a positioning mechanism for the matrix case of a record strip controlled single-type casting and composing machine, or for the master plate of a photo-typographical composing machine, the combination of a pair of positioning levers, a stepped series of positioning gauge 25 pins, separately projected into the path of the aforesaid jaws under control of the record strip, a jaw on each of said levers arranged to engage a projected pin of the stepped series, a supplementary jaw hinged to the jaw on one of the positioning levers, a rockable bar guide for the supplementary jaw, an air piston connected to the rockable bar and controlled from the record strip to move the supplementary jaw into and out of position either to engage or override a projected gauge pin and a locking device for the rockable bar.
